United States Patent Office

Des. 222,126
Patented Oct. 5, 1971

222,126

COLLAPSIBLE TUBE OR THE LIKE

William Sheehan, 146—14 45th Ave.,
Flushing, N.Y. 11355

Filed Apr. 2, 1970, Ser. No. 22,209

Term of patent 14 years

Int. Cl. D9—06

U.S. Cl. D9—194

FIG.1

FIG.2

FIG.4

FIG.3

FIG. 1 is a top plan view of the collapsible tube or the like;

FIG. 2 is a front elevational view thereof, the back of the collapsible tube being substantially the same;

FIG. 3 is a bottom plan view thereof, and

FIG. 4 is a view of one side thereof, the other side being substantially the same.

I claim:

The ornamental design for a collapsible tube or the like, as shown and described.
